(57) **CLAIM**

The ornamental design for a grate, as shown and described.

DESCRIPTION

FIG. 1 is a top perspective view of a grate showing my new design;

FIG. 2 is a top plan view of the grate shown in FIG. 1, the bottom plan view being identical thereof;

FIG. 3 is a front elevation view of the grate shown in FIG. 1, the rear elevation view being identical thereof; and, FIG. 4 is a right elevation view of the grate shown in FIG. 1, the left elevation view being a mirror image thereof.
